UNITED STATES PATENT OFFICE.

CHARLES A. KUHLMAN, OF RICHMOND, INDIANA.

WARDROBE-HOOK.

SPECIFICATION forming part of Letters Patent No. 296,696, dated April 8, 1884.

Application filed February 4, 1884. (No model.)

To all whom it may concern:

Be it known that I, CHARLES A. KUHLMAN, a citizen of the United States, residing at Richmond, in the county of Wayne and State of Indiana, have invented certain new and useful 5 Improvements in Wardrobe-Hooks, of which the following is a specification, reference being had therein to the accompanying drawings.

10 My invention relates to that class of wardrobe-hooks used for hanging up garments.

My invention consists in making the arm of the hook movable, and in providing the same with a spring to hold the same in position and 15 to restore it to a vertical from a horizontal position.

In the drawings, Figure 1 is a rear elevation of my improvement. Fig. 2 is a side elevation, showing the arm in both vertical and horizontal position. Fig. 3 is a bottom plan view of 20 the cap which covers the recess in Fig. 1.

In Fig. 1, *a* represents a metallic plate, octagonal in its outline form, having a rectilinear chamber, *i*, in its center, and provided with 25 holes for screws to secure it to a wall. *b* is a hinged arm attached to a shaft, *c*, at right angles at one end, and terminating in a curved form at the other, mounted with a hemispherical button, *m*. The shaft *c* has its end bear-

ings in the shoulders of the chamber *i*, and is 30 bedded in said chamber to the extent, or nearly so, of its diameter. A coiled spring, *e*, is placed around one end of the shaft *c*, one end of which is held by a groove in the side of the chamber *i*, while the other end is attached to the shaft 35 *c*. The action of this spring is to hold the arm *b* in a vertical position parallel with the face of the plate *a* when not in use, and to restore it to that position after being brought down in use, as shown in dotted lines in Fig. 2. 40

In Fig. 3, *d* represents a cap intended to cover the chamber *i*, and having a semicircular concave, *c'*, to fit over the shaft *c*, and allow the cap to fit the opening of the chamber *i*, flush with the face of the same. 45

Having thus fully described my improvement, what I claim as new, and desire to secure by Letters Patent, is—

A wardrobe-hook composed of the plate *a*, arm *b*, shaft *c*, and spring *e*, constructed and 50 operating in the manner and for the purposes set forth.

In testimony whereof I affix my signature in presence of two witnesses.

CHARLES A. KUHLMAN.
